JAR OR THE LIKE

Bryant Edwards, Clarendon Hills, Ill., assignor to Illinois
Tool Works Inc., Chicago, Ill.

Filed Apr. 26, 1972, Ser. No. 247,935

Term of patent 14 years

Int. Cl. D9—01

U.S. Cl. D9—140

FIG. 1 is a side elevational view of a jar showing my new design;

FIG. 2 is a top plan view;

FIG. 3 is a bottom plan view; and,

FIG. 4 is an enlarged fragmentary cross sectional view taken along the line 4—4 of FIG. 3.

I claim:

The ornamental design for a jar or the like, as shown.
